CLAIM

The ornamental design for point-of-sale base with object recognition camera module thereon, as shown and described in the drawings.

DESCRIPTION

FIG. 1 is a perspective view of point-of-sale base with object recognition camera module thereon showing this new design;

FIG. 2 is a second perspective view thereof;

FIG. 3 is a third perspective view thereof;

FIG. 4 is a front view thereof;

FIG. 5 is a back view thereof;

FIG. 6 is a left view thereof;

FIG. 7 is a right view thereof;

FIG. 8 is a top view thereof; and,

FIG. 9 is a bottom view thereof.

This patent application is applied for a partial design in USA, so it will be understood that the broken lines depict portions of the point-of-sale base with object recognition camera module thereon that form no part of the claimed design.
